UNITED STATES PATENT OFFICE.

WILLIAM F. HELMOND, OF HARTFORD, CONNECTICUT, ASSIGNOR TO UNDERWOOD TYPEWRITER COMPANY, OF NEW YORK, N. Y., A CORPORATION OF DELAWARE.

TYPEWRITING MACHINE.

Application filed December 29, 1922. Serial No. 609,560.

To all whom it may concern:

Be it known that I, WILLIAM F. HELMOND, a citizen of the United States, residing in Hartford, in the county of Hartford and State of Connecticut, have invented certain new and useful Improvements in Typewriting Machines, of which the following is a specification.

This invention relates to continuous billing mechanism for type writing machines, and is illustrated in connection with a book-keeping machine of the Underwood-Hanson type. Certain features of the invention are not limited to bookkeeping machines, however, but are applicable to continuous billing machines in general, in which printed forms are usually repeated along each ply of a multiple-ply web, to be torn off one by one when typed, the web being usually of the fan-fold type.

When fan-fold mechanism or the like is applied to a bookkeeping machine of the type referred to, the webs must be guided above the usual housings of the sets of denominational jacks, which makes it difficult sufficiently to straighten the webs as they extend under the raised platen, to permit the carbons to be freely drawn back by the usual carbon-carriage. In accordance with one feature of the present invention, provision is made of means for swinging the displaceable platen to an elevated position about an axis more remote from the platen than the axis of the platen-driving pinion about which the platen has been swung in previous machines. This enables the platen to be raised to a greater height, and hence the webs may be straightened out, even though they are arranged at a high elevation above the adding mechanism at the rear of the machine. One of the features is the disengagement of the platen-gears from the platen-driving pinions when the platen is so elevated. Provision is made for re-engagement of the gears and pinions when the platen is again lowered, the gears being arranged to swing easily into mesh with the pinions, and all being provided with sharp-pointed teeth, to avoid clashing.

The rear frame-extension of the usual continuous billing machine for supporting the rear carriage-extension adds considerably to the bulk of the machine, making it of an inconvenient shape to store or ship.

This is emphasized in the case of a book-keeping machine. A feature of the invention is the provision of a rearwardly-extending bracket, for supporting the rear carriage extension, pivoted at its lower end to the supporting stand of the machine, and capable of being swung down out of the way when not in use.

It has been found that the momentum of the rear carriage-extension or table, in tabulating operations, is apt to cause a twisting of the carriage which is sufficient to cause the denomination-selector to engage the wrong jack. This occurs even when the tabulating and escapement mechanism function properly, and causes incorrect results to be exhibited. This difficulty may be overcome by the provision of plates on the rear carriage-extension for engaging the rear guiderrail of the supporting bracket, to limit the swinging movement referred to.

Another feature of the invention is the provision of an improved form of guide for the work-webs.

While the foregoing provision is made for giving the platen an elevation much higher than heretofore practiced, for permitting the straightened webs to clear the adding mechanism, still the improvements may also be used without change in a simple typewriting machine, whereby one set of attachments may answer for either machine, thus conducing to economy of manufacture and handling.

Other features and advantages will hereinafter appear.

In the accompanying drawings,

Figure 1 is a sectional side elevation of a portion of a bookkeeping machine having the present improvements applied thereto.

Figure 2 is a side elevation, on a larger scale than Figure 1, of the means for guiding the rear carriage-extension and limiting the swinging movement thereof.

Figure 3 is a plan view of the parts shown in Figure 2, with the carriage-extension omitted.

Figure 4 is a plan view of the carriage and carriage-extension of the machine.

Figure 5 is a fragmentary side elevation, showing the supporting frame, with the carriage-extension-supporting bracket swung to lowered position.

Figure 6 is a side elevation of the platen-frame, showing the platen in a position to

have the teeth of its gears re-engage the teeth of the platen-rotating pinions.

Figure 7 is a rear elevation of the machine.

5 Figure 8 is a fragmentary front elevation, showing the denomination-selector and the denominational jacks.

Figure 9 is a perspective view of the improved web-guide.

10 In a bookkeeping machine of the Underwood-Hanson type, a typewriter 11, having a frame 12, rests on a casing 13 of a computer, which is controlled by the numeral-keys of the typewriter, and the computer-casing 13 rests on a stand, comprising a top 14 and supporting posts or legs 15.

The typewriter 11 comprises a platen 16 mounted on a platen-axle 17, which is rotatably supported in a traveling carriage 18. The carriage 18 is supported at its rear on a rail 19 fixed on the typewriter-frame 12. Provision is made of brackets 20, attached to the rear of the typewriter-frame 12, at each side thereof, and carrying at 25 their upper ends a bar 21, on which may be supported one or more sets of denominational jacks 22 and a housing 23 for each set of such jacks. At the rear of each housing 23 a casing 24 for the usual thrust-rods 30 (not shown) extends downwardly to the rear of the computer-casing 13 and is attached thereto.

The carriage 18 is provided at its rear with brackets 25 extending rearwardly and 35 outwardly, and having upwardly-extending ends, in which are mounted a rod 26, along which a denomination-selector 27 may be moved, and a notched rod 28 having its notches at letter-space distances, the denomination-selector being held in adjusted positions by engagement of a tooth 29 thereon in the notches of the rod 28. When the carriage 18 is traveling through a computing zone, a tappet 30, carried by the denomination-selector 27, engages successively the forward ends of the denominational jacks 22 and selects the denominations in which digits are to be indexed. The computing mechanism and the denomination-selecting mechanism, forming part thereof, may be, in general, similar to that disclosed in the patent 40 to Richard M. Becker, No. 1,296,354, granted 45 March 4, 1919.

50 Inasmuch as the present invention contemplates the use in a bookkeeping machine of the features of a continuous billing machine, the axle 17 of the platen 16 is journaled in the ends 31 of a platen-displacing frame 32, said ends being extended forwardly and 55 upwardly, and being pivoted by such extended portions upon stub-shafts 33, mounted on the frame of the carriage 18, at the front of, and considerably above, the normal 60 position of the platen-axle 17. The platen-axle 17 is provided at its ends with gears

34, which mesh with broad pinions 35, pivoted on short shafts 36 on the frame of the carriage 18. The broad pinions 35 also mesh with gears 37 similar to the gears 34 and fixed on the inner ends of stub-shafts 38 journaled in the frame of the carriage 18. The platen 16 may be rotated by means of either of the finger-wheels 39 or by the usual line-spacing mechanism. When the webs, indicated in general by 40, are to be straightened under the platen to permit the withdrawal of the interleaved carbon-sheets in the usual manner, the platen 16 is swung upwardly with the assistance of a counter-balance spring 33^a about the shafts 33 to the 70 position shown in Figure 1, the webs then being drawn forward and gaged by means of the usual gage 41, adjustable on the gage-bar 42, mounted on a front paper-table 43 which forms part of the platen-displacing frame 32. Since the displacing frame 32 is not swung about the axis of the stub-shafts 36, on which the pinions 35 are mounted, it will be apparent that the gears 34 will be carried out of mesh with the pinions 35 in the course of the displacing movement. In order to insure re-engagement so that the platen may be returned to its normal, lowered position, without opposition, the teeth of both the gears 34 and pinions 35 are made with sharp points. Yielding abutments or stops 44 of rubber or other suitable material are mounted on the carriage 18 to be engaged by stops 44^a on the platen-displacing frame 32 for limiting the 80 outward swinging movement thereof.

At the rear of the machine, provision is made of a carbon-carriage 45, mounted for movement toward and from the platen, upon a rear carriage-extension or table 46 comprising a front member 47, secured by screws 48 to brackets 49 extending rearwardly from the carriage 18, a rear member 50 and a plurality of connecting members 51 having on the upper sides thereof rails 52, with each one of which co-operate grooved rolls 53, mounted on the base-plate 54 of the carbon-carriage 45. The carbon-carriage 45 may be moved to the rear by a handle 55 in the usual manner. This handle may be corrugated to increase its rigidity, as shown in Figure 1. To support and guide the rear carriage-extension 46 at its rear end, provision is made of a guide-rail 56, mounted on a rear bracket 57 and extending parallel to the guide-rail 19. Each of the members 51 has an angle-plate 58 attached to it, having a downwardly-extending portion, and each plate 58 carries a roller 59 which rides upon the rail 56 and a guide 60 which partially embraces the rail 56. For the purpose of preventing excessive swinging movement of the carriage, at the conclusion of a tabulating operation, and consequently of preventing interference 90 95 100 110 115 120 125 130

with the proper operation of the denomination-selecting mechanism, the plates 58 are provided with lateral extensions 61 to lie to the rear of the rail. These extensions are 5 positioned to engage the rail 56 when the carriage has been swung only a slight amount and in co-operation with the guides 60 to limit the swinging movement of the carriage and carriage-extension, the plate 10 58 at one side of the carriage-extension and the guide 60 at the opposite side thereof having a tendency to bind the guide-rail 56 between them when the carriage is swung.

The bracket 57, upon which the rail 56 is 15 mounted, comprises two upwardly and rearwardly inclined bars 62, pivotally mounted at their lower ends upon a shaft 63, carried by lugs 64 on the top 14 of the supporting frame. The bars 62 are connected to each 20 other by a cross-bar 65 and are detachably connected to the typewriter-frame 12 by rods 66, which are threaded into the typewriter-frame at their forward ends, and which receive in threaded sockets at their rear ends 25 screws 67 to secure them to the bars 62. When it is desired to reduce the size of the machine, for shipping or for other purposes, the rear carriage-extension 46 may be disconnected from the brackets 49 by removing 30 the screws 48, and may then be slid off the guide-rail 56. The supporting rods 66 of the bracket 57 may be quickly disconnected from the machine-frame 12 and from the bracket 57, to permit the bracket to be 35 swung down about the shaft 63 to the position indicated in Figure 5.

A bar 68 having a flat face 69 extends across the carriage 18 between the brackets 49 and members 70, of novel construction, 40 for guiding the work-webs 40 are adjustably mounted upon the bar 68. Each guiding member 70 comprises upstanding legs 71 and 72 connected by a cross-bar 73 the legs having holes 74 therethrough of a shape 45 to conform to the shape of the supporting bar 68. The legs 71 and 72 and the cross-bar 73 are split beneath the holes 74, the arrangement being such that the legs resiliently grip the supporting bar 68 and yieldably resist movement of the guide 70 along 50 the rod. The flat portions of the supporting bar and of the holes in the legs of the guides prevent turning of the guides upon the supporting bars.

55 Variations may be resorted to within the scope of the invention, and portions of the improvements may be used without others.

Having thus described my invention, I claim:

60 1. In a front-strike web-typewriting machine, the combination of a revoluble platen, a carriage therefor, means at the introductory side of the platen and connected to said carriage to present a work-web to the platen, 65 a carbon-stripper movable along the web,

said platen normally far below the level of the web at the introductory side of the platen, a platen-line-space wheel upon said carriage, a pinion mounted upon said carriage and connected to the line-space wheel, 70 said platen having upon its end a gear normally meshing with said pinion, and a platen-frame hinged upon said carriage to swing the platen and platen-gear up away from said pinion and to a position above 75 the straightened-out web, preparatory to stripping the carbons that are interleaved with the plies of web.

2. In a front-strike web-typewriting machine, the combination of a revoluble platen, 80 a carriage therefor, means at the introductory side of the platen and connected to said carriage to present a work-web to the platen, a carbon-stripper movable along the web, 85 said platen normally far below the level of the web at the introductory side of the platen, a platen-line-space wheel upon said carriage, a pinion mounted upon said carriage and connected to the line-space wheel, 90 said platen having upon its end a gear normally meshing with said pinion, and a platen-frame hinged upon said carriage to swing the platen and platen-gear up away from said pinion and to a position above 95 the straightened-out web, preparatory to stripping the carbons that are interleaved with the plies of web, said platen being freely revoluble when disconnected from said pinion, and said gear and pinion having pointed teeth to avoid clashing and to insure easy meshing of the gear with the pinion when the platen is lowered to typing position.

3. In a front-strike web-typewriting machine, the combination of a revoluble platen, 105 a carriage therefor, means at the introductory side of the platen and connected to said carriage to present a work-web to the platen, a carbon-stripper movable along the web, 110 said platen normally far below the level of the web at the introductory side of the platen, a platen-line-space wheel upon said carriage, a pinion mounted upon said carriage and connected to the line-space wheel, 115 said platen having upon its end a gear normally meshing with said pinion, and a platen-frame hinged upon said carriage to swing the platen and platen-gear up away from said pinion and to a position above 120 the straightened-out web, preparatory to stripping the carbons that are interleaved with the plies of web, said carriage having at its ends arms extending upwardly and forwardly above said pinion, and said platen-swinging frame having upwardly and forwardly extending end members pivoted at their upper ends to the upper ends of said carriage arms.

4. In a front-strike web-typewriting machine, the combination of a revoluble platen, 130

a carriage therefor, means at the introductory side of the platen and connected to said carriage to present a work-web to the platen, a carbon-stripper movable along the web, said platen normally far below the level of the web at the introductory side of the platen, a platen-line-space wheel upon said carriage, a pinion mounted upon said carriage and connected to the line-space wheel, said platen having upon its end a gear normally meshing with said pinion, and means for swinging the platen away from the pinion about an axis which is above and beyond the axis of the pinion to a position above the plane of the straightened-out work-web, said plane being substantially above said pinion.

5. In a typewriting machine, a gage-supporting bar, and a side gage for a work-sheet, said gage comprising a cross-bar and two arms extending perpendicularly from said cross-bar, said arms having holes therein through which the supporting bar may extend, said gage having a slot extending from said holes through said arms and said cross-bar to enable the gage to be sprung onto and grip the supporting bar.

6. In a typewriting machine, the combination of a carriage, a table extending rearwardly from said carriage, means comprising a guide-rail to support said table, tabulating mechanism for said carriage, carriage-supporting devices embracing said guide-rail, and rail-engaging projections extending a considerable distance lengthwise of said rail from said carriage-supporting devices, to prevent excessive lateral overthrow of the rear end of said table when the carriage is arrested at the tabulating operation.

35. 7. In a typewriting machine, the combination of a carriage, a table extending rearwardly from said carriage, a guide-rail to support and guide said table, tabulating mechanism for said carriage, and elongated devices on the table adjacent the guide-rail and movable into frictional engagement therewith when the table is swung away from normal position, to oppose such swinging movement.

40. 8. In a typewriting machine, the combination of a carriage, a rear extension thereof, a guide-rail to support and guide the carriage-extension, tabulating mechanism for said carriage, and means ineffective to retard the travel of said carriage-extension but effective to damp the lateral swinging movements of the carriage-extension at the conclusion of tabulating operations to bring it quickly to rest.

50. WILLIAM F. HELMOND.
